CLAIM

The ornamental design for a fabric, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top plan view of a fabric; and,

FIG. 2 is the enlarged portion of area 2 in FIG. 1.

The dash dot dash broken lines around FIG. 1 depict the boundaries of the claim and form no part thereof. The de-emphasized area outside of the boundary line depicts a portion of the fabric that forms no part of the claimed design. The dash dot broken line within the boundaries of the claim denotes the boundary of the area of the detail and forms no part of the claimed design.
